UNITED STATES PATENT OFFICE.

JOHN L. ARTER, OF SUNBURY, PENNSYLVANIA.

SAFETY DEVICE FOR CAR-COUPINGS.

SPECIFICATION forming part of Letters Patent No. 527,136, dated October 9, 1894.

Application filed May 22, 1894. Serial No. 512,048. (No model.)

To all whom it may concern:

Be it known that I, JOHN L. ARTER, a citizen of the United States, residing at Sunbury, in the county of Northumberland and State 5 of Pennsylvania, have invented certain new and useful Improvements in Safety Devices for Car-Couplings, of which the following is a specification.

In the use of safety car couplers commonly 10 known as the "Janney-type" couplers accidents frequently happen caused by the breakage of the car coupler or draw-head, the part broken off dropping upon the track and thereby causing the derailment of, or injury to 15 cars in the rear of the broken coupler. These couplers as at present constructed are not provided with means for interlocking them vertically and hence, if one of them breaks, as above described, or is pulled away from 20 its car, it is free to drop upon the track.

My invention relates to a safety device whereby the engaging couplers of cars are interlocked vertically, that is to say, either coupler will sustain the other and prevent it from 25 falling to the ground in case of accidents such as those above outlined.

The invention consists more particularly in a latch pivoted to the upper side of the coupler and arranged to be turned so as to over- 30 hang the interlocking coupler in case of accident to the coupler to which it is attached.

I shall now proceed to describe the preferred form of my invention, reference being had to the accompanying drawings, in which—

35 Figure 1 is the plan view of a pair of couplers interlocked and provided with my invention. Fig. 2 is a perspective view of a single coupler provided with the invention; and Fig. 3 is a side view of the preferred form of latch.

40 Referring to the drawings A, A' indicate a pair of couplers attached respectively to cars B, B'; and C, C' indicate the hinge pins of the couplers. My improved latch consists, as shown, of a disk or ring D having a central 45 perforation through which the hinge pin passes, an eye d upon one side and an arm E upon the other. The arm E is preferably ele- 50 vated upon an upright or a standard e, so that in coupling or uncoupling it will be out of the way and will not interfere even if the couplings are of different sizes or if one is slightly higher than the other.

As shown, the eye d, is connected by means of a chain F with a staple f, in the woodwork of the car. When the coupler is in place 55 upon the car, the latch is turned to one side as shown upon the coupler A' in the drawings, so as not to interfere with the operation of the coupler. The chain is just long enough to permit the latch to assume this position. 60 If, however, the coupler or draw head should break or pull out from the car the latch will be immediately thrown around over the adjacent coupler by the tightening of the chain after which the chain will break or the staple pull out. In Fig. 1 of the drawings, the coupler A is thus shown, the drawhead being pulled out from the car and the staple also pulled out from the sill or part to which it was fastened. It will be seen that the arm 70 E of the latch upon the coupler A overhangs the coupler A' and that should the coupler A be separated entirely from the car B, it would be prevented from dropping to the ground. In such case, it would remain in- 75 terlocked with the coupling A', its weight resting partially upon the latch arm E.

While I have simply shown and described the preferred form of my invention, it will be evident that many other forms within the 80 spirit thereof may be constructed. For instance, the latch may be pivoted to some other portion of the coupling, or it may be a sliding latch instead of a pivoted latch. The main features of the invention consist in a 85 safety latch and means for projecting the latch upon one coupler into engagement with the interlocking coupler in case of accident to the coupler having the latch, or its draw- 90 head.

Without therefore limiting myself to the precise construction and arrangement of parts shown and described, I claim—

1. The combination with a car coupler of the class described, of a safety latch and 95 means for projecting said latch into engagement with an interlocking coupler in case of breakage of the draw head or coupler to which it is attached, for the purpose described.

2. The combination with a car coupler of 100 the class described, of a safety latch pivoted thereto and means whereby said latch is turned into position to engage an interlocking coupler in case of breakage of the draw

head or coupler to which it is attached, for the purpose described.

3. The combination with a car coupler of the class described, of a latch pivoted to the coupler and having an arm adapted to overhang the adjacent coupler and a chain or connection between said latch and the car, substantially as described.

4. The combination of a car coupler of the class described, of a safety latch consisting of a ring or disk having a perforation and

mounted upon the hinge pin of the coupler, an arm adapted to overhang the adjacent coupler, an eye opposite the arm and a chain or connection uniting said eye to the car body, 15 substantially as described.

In testimony whereof I affix my signature in presence of two witnesses.

JOHN L. ARTER.
